UNITED STATES PATENT OFFICE.

ALBERT H. STEBBINS, OF LOS ANGELES, CALIFORNIA.

PNEUMATIC SIZER.

Application filed April 8, 1922. Serial No. 550,871.

To all whom it may concern:

Be it known that I, ALBERT H. STEBBINS, a citizen of the United States, residing at Los Angeles, in the county of Los Angeles 5 and State of California, have invented an Improvement in Pneumatic Sizers, of which the following description, in connection with the accompanying drawings, is a specification, like characters on the drawings representing like parts.

This invention relates to pneumatic sizers or separators for the separation of materials in accordance with their size and specific gravity.

Heretofore the sizing of materials has been commonly accomplished by the use of screens, the materials to be treated being passed over the screening surface so that the fine materials will pass through the apertures of the screen out of contact with the coarse materials. Screens however are open to the objection that it is difficult to prevent the mesh thereof from clogging, and the screen clothing wears out rapidly. Furthermore, 25 more screens will not separate materials in accordance with their differences in specific gravity.

In the separation of certain classes of materials, such for example as in the treatment of ores it may be desirable to separate the materials in accordance with the differences in size, and also to produce a partial separation in accordance with the differences in specific gravity. This can not be done upon the ordinary screen as screens 30 separate in accordance with size alone.

One important feature of the present invention therefore consists in novel means for delivering materials to a jet of air so 40 that the light materials will be deflected to a greater extent than the heavy materials.

In the treatment of different materials it may be desirable to vary the conditions under which the materials are subjected to 45 the action of the air. Other features of the invention therefore consist in means for subjecting the materials to be sized to a plurality of jets of air the strength of which may be controlled as desired; in means which 50 may be adjusted relative to the deflecting jets of air to vary the point at which the light deflected materials are separated from the heavier materials; and in means for drawing air through the materials being

treated further to promote their separation. 55

And still another feature of the invention consists in means arranged in series for subjecting the materials separated out in the first operation to a second and similar treatment. 60

Other features of the invention and novel combination of parts in addition to the above will be hereinafter described in connection with the accompanying drawings which illustrate good practical forms 65 thereof.

In the drawings:

Fig. 1 is a side elevation of a pneumatic sizer constructed in accordance with the present invention, one side of the enclosing 70 casing being removed to disclose the interior thereof.

Fig. 2 is a perspective view of an air discharge nozzle.

Fig. 3 is a perspective view of a modification of the pneumatic sizer of Fig. 1, one side of the casing being removed, and 75

Fig. 4 is a vertical sectional view showing a modification in the construction of Fig. 3. 80

In the embodiment of the invention illustrated in Fig. 1, a casing is provided containing two sizing or separating chambers arranged in series so that part of the materials treated in the first chamber 10 are 85 delivered to a second chamber 11 where they receive a second treatment. It will be apparent however that for certain purposes the treatment to which the materials are subjected in the chamber 10 may be sufficient without requiring the use of the second chamber 11, whereas in other cases it may be desired to provide more than two of the separating chambers arranged in series for the successive treatment of the materials. 90

The casing containing the chambers 10 and 11 may be variously constructed, and in the embodiment shown is provided with an inclined lower wall 12 for directing the materials to be treated into the chamber 10 100 and a second inclined lower wall 13 for directing materials from the chamber 10 into the chamber 11. Spaced above the walls 12 and 13 are the upper walls 14 and 15 of the casing, and the far side of the casing, is closed by the wall 16 while the near side may be closed by a similar wall 105 not shown. The materials to be treated

are fed to the chamber 10 by the hopper 17, preferably provided with an adjustable gate 18 to control the flow of materials into the chamber.

5 As stated, separation of the materials is effected in the present invention by subjecting them to the action of one or more jets of air so that different materials will be deflected differently, and to this end, in the 10 construction shown, the inclined wall 12 serves to direct the materials to be treated across the path of air discharged from one or more nozzles. In Fig. 1 four nozzles 19 are provided arranged one above the other, 15 and each nozzle has air or other fluid delivered thereto under pressure by a pipe 20, valves 21 being provided to regulate the discharge from each nozzle. The number of nozzles 19 provided may be varied as desired and each nozzle preferably has a wide flattened end as shown in Fig. 2 adapted to discharge air therefrom in the form of a sheet.

As the materials pass down the inclined 25 surface 12 they are delivered into the path of the air discharged from the nozzle or nozzles 19 and are deflected by the force of the air. The light particles will be deflected to a greater extent than the heavy particles, 30 and this enables separation of the materials to be effected by providing a partition 22 in spaced relation to the nozzles 19 so that the lighter materials will be carried by the air over this partition while the heavier particles will fail to be lifted over the same.

As a result of this construction the heavy 35 particles will fall in the chamber or compartment 23 to one side of the partition 22 while the light materials will fall in the 40 chamber or compartment 24 to the other side of this partition.

By providing a nest or group of air jets 45 that act simultaneously upon the same particles, the particles are thoroughly cleansed, and the desired amount of deflection of the materials is produced without the use of an unduly strong air blast. Furthermore by providing means for controlling the strength of each air jet, the cleansing and 50 deflecting operation of the air may be varied to meet the requirements of various materials.

It may be desirable to vary the percentage 55 of the materials that fall into one compartment or the other and this may be readily accomplished by changing the position of the partition 22. In the construction shown the partition 22 is pivotally mounted at 25 upon a plate 26 and may be 60 adjusted toward or from the nozzles 19 from the exterior of the chamber 10 by means extending through the curved slot 27 in the rear wall 16. It may also be desirable to vary the height of the partition 22, and 65 this may be accomplished by providing the

partition with an adjustable extension 28 secured in place by a clamping nut 29. Further adjustment of the partition 22 may be obtained by a sliding adjustment of the plate 26.

The compartment 23 may be provided 70 with a spout 30 at its lower end through which the materials are discharged, and the materials within the compartment 24 escape therefrom along the inclined surface 75 13. It is desirable to remove the dust from the chamber 10 and also to reduce the air pressure therein so that air will not be forced out of the discharge openings of the compartments 23 and 24. A conduit 31 is 80 therefore provided leading from the chamber 10. This conduit may be connected to any suitable exhaust pipe 32, and passage of air through the conduit may be controlled by an adjustable gate 33. It is desirable to prevent air from entering through the discharge outlets of the compartments 85 23 and 24 and, to this end the outlets are provided with air traps 34 and 35 respectively.

In some cases it may be desirable further 90 to separate the materials collected in the compartment 24 and to this end these materials are passed along the surface 13 into the second chamber 11 where they are subjected to the action of an air blast or air 95 blasts discharged from the nozzle or nozzles 36. The lighter materials in this chamber will be carried over the partition 37 as in the chamber 10, and the construction and 100 operation in this chamber may be substantially the same as in chamber 10 except the force of the air will be less in the second chamber than in the first.

The heavier materials treated in chamber 11 will fall into compartment 38 having an air trap 39, and the lighter materials will fall into compartment 40 having an air trap 41. A conduit 42 leading from the chamber 11 to the pipe 32 serves to reduce the air pressure in this chamber and to conduct dust therefrom, and the air suction in this conduit may be controlled by an adjustable 110 gate 43.

It may be desirable to introduce more air 115 into the chambers 10 and 11 than is supplied thereto by the nozzles 19 and 36 respectively. An air inlet 44 is therefore provided below the bottom nozzle 19 for admitting air into the chamber 10 and the size of this 120 inlet may be controlled by the adjustable gate 45. The arrangement is such that air drawn in through the inlet 44 will pass up through the materials being treated and will help to clean and separate the materials. 125 The chamber 11 may be provided with a similar inlet opening 46.

The construction and operation of the pneumatic sizer shown in Figs. 3 and 4 differs in certain respects from the construc- 130

tion and operation of the pneumatic sizer of Fig. 1. The principal difference being that the modified construction of Figs. 3 and 4 is designed to treat finer or lighter materials than the construction of Fig. 1.

In the treatment of certain materials it may be desirable to separate the materials into a number of different grades. The casing of Fig. 3 is therefore shown as having the separating chambers 47 and 48 each of which is divided by partitions into several compartments. The materials to be treated in chamber 47 are supplied thereto by the hopper 49 and the materials pass down the inclined surface 50 into the path of a jet of air delivered by the nozzle 51. Materials differing in size and specific gravity will be deflected differently by the air jet from the nozzle 51. The heaviest materials will fall into the compartment 52 while the lighter materials will fall into the compartments 53 and 54, and these compartments may be separated by adjustable partitions 55 and 56 similar to the partition 22 of Fig. 1.

In some cases it may be desirable to pass air through the materials as they travel along the inclined surface 50, as this will tend to fluff the materials up and to remove dust therefrom. To this end the surface 50 may be provided with apertures for the passage of air therethrough and air under pressure may be supplied to the lower face of this surface by the chamber 57 and air supply pipe 58.

In certain cases it may be desirable to remove part of the dust carried from the chamber 47, and to this end any desired type of dust collector 59 may be connected to the chamber 47. In the construction shown the upper end of the dust collector 59 is connected to an air exhaust pipe 60 by a conduit 61 and the dust that settles in the dust collector will slide down the inclined walls 62 and fall into the compartment 54. An additional supply of air may be admitted to the chamber 47 through the opening 63 below the nozzle 51 in a manner similar to that described in connection with Fig. 1.

The materials collected in the compartment 52 may be discharged through the spout 64 having an air trap 65 and the materials collected in the compartment 54 may be discharged through the spout 66 having an air trap (not shown).

In cases when it is desired to treat further the materials deposited in any of the compartments of the chamber 47, the materials may be lead from the compartment 53, (for example) to the chamber 48 where the materials will be further separated by mechanism similar in construction and operation to the mechanism of the first chamber 47.

If desired the chamber 47 and 48 may be provided with a plurality of air supply noz-

zles 51 as shown in Fig. 4 in place of the single nozzle for each chamber as shown in Fig. 3.

What is claimed is:—

1. In a pneumatic sizer, in combination, a casing provided with separate closed chambers, means for delivering a jet of air into the first chamber, means for delivering a jet of air into the second chamber, partitions within said chambers in spaced relation to the respective jet delivery means, means for delivering materials to be treated into the path of the jet of air in the first chamber that the lighter materials may be carried by the air over the partition, means for directing the materials falling upon one side of said partition into the path of the jet of air in the second chamber to further grade the materials, and means for preventing air from flowing from one chamber to the other.

2. In a pneumatic sizer, in combination, a casing provided with separate chambers, a group of nozzles for directing a series of air jets into the first chamber, a different group of nozzles for directing air jets into the second chamber, partitions within said chambers in spaced relation to the respective groups of nozzles, means for delivering materials to be treated into the path of the jets of air in the first chamber to subject the materials to the cleansing action of the different jets and that the lighter materials may be carried by the air over the partition, and means for directing the materials falling upon one side of said partition into the path of the air jets in the second chamber to subject them to the additional cleansing action of these jets and further to grade the materials.

3. In a pneumatic sizer, in combination, a casing having an inclined apertured surface along which the materials to be treated are fed, an air jet for directing a sheet of air into intersecting relation with the path of the materials, a partition in the casing spaced from the air jet so that the lighter materials will be deflected over the partition while the heavier particles will fail to pass over the partition, and means for passing currents of air upwardly through the materials upon the apertured surface to fluff them up as they travel along said surface.

4. In a pneumatic sizer, a casing for directing materials fed thereto along a predetermined path, a nest of air jets for directing air currents of different velocities into intersecting relation with the path of the materials to subject the materials to the cleansing action of the different strength jets, a partition in the casing spaced from the air jets and positioned so that the lighter materials will be carried over the partition by the air jets, and means for varying the strength of the different air jets to vary their cleansing action upon the materials and to

- vary the grades of materials that fall upon different sides of the partition.
5. In a pneumatic sizer, in combination, a casing having an inclined apertured surface along which materials to be treated are fed, air nozzles arranged side by side in a series for delivering adjacent sheets of air into the casing, means for independently controlling the force of the air delivered by each nozzle, partitions within said casing forming different chambers, means for delivering materials to said inclined surface to travel along the surface into the path of the adjacent sheets of air that different materials may be carried by the air over different partitions, and means for passing currents of air through said apertured surface to fluff up the materials as they travel along said surface.
- 10 6. In a pneumatic sizer, a casing having a surface for directing materials along a pre-determined path, partitions within the casing forming different chambers therein, a nest of air jets for delivering sheets of air differing in velocity into intersecting relation with the materials traveling along said path to subject the materials to the cleansing

action of the cooperating jets and to deflect the materials from their path of travel, and means for varying the velocity of each jet of air to cause some jets to break up the density of the materials and others to cleanse the materials and to lift the lighter materials sufficiently to pass over different partitions.

30 7. In a pneumatic sizer, in combination, a casing, a plurality of air nozzles arranged one above the other in a series for delivering adjacent sheets of air into the casing, a partition within the casing, means for delivering materials to be treated into the path of the adjacent sheets of air to subject the materials to the cleansing action of the cooperating jets and so that the lighter materials will be lifted over said partition while the heavier materials will fail to be lifted over the partition, and means for independently controlling the force of the air delivered by each nozzle so that some jets will break up the density of the materials and others will cleanse and deflect the materials.

40 45 In testimony whereof, I have signed my name to this specification.

ALBERT H. STEBBINS
